UNITED STATES PATENT OFFICE.

EDWIN WALKER KELLY, OF PHILADELPHIA, PENNSYLVANIA, ASSIGNOR, BY MESNE ASSIGNMENTS, TO VICTOR ELECTRIC CORPORATION, OF CHICAGO, ILLINOIS, A CORPORATION OF NEW YORK.

METHOD OF AND APPARATUS FOR CONTROLLING THE RESISTANCE OF AN X-RAY TUBE.

1,285,215.

Specification of Letters Patent. Patented Nov. 19, 1918.

Application filed December 28, 1913. Serial No. 808,668.

To all whom it may concern:

Be it known that I, EDWIN W. KELLY, a citizen of the United States, residing in the city and county of Philadelphia, State of Pennsylvania, have invented certain new and useful Improvements in Methods of and Apparatus for Controlling the Resistance of X-Ray Tubes, of which the following is a specification.

10 My invention relates to a method of and apparatus for controlling the behavior of vacuum tubes, and more particularly X-ray tubes.

It has long been known that the vacuum 15 or highly rarefied air remaining in a glass bulb which has been highly exhausted is a very perfect non-conductor of electricity and that even a potential as high as that ever impressed on an X-ray tube will not 20 send a discharge between electrodes within the bulb if the exhaustion has been pushed far enough. And it has further been long known that if in such a highly exhausted bulb electrodes are provided, for example 25 one of them a metal plate and the other a carbon filament, like an incandescent lamp filament, no discharge will pass between the filament and plate when the filament is cold, but, when the carbon filament is rendered 30 incandescent as by passing a current through it, it is found that even slight potentials, such as developed by a single cell of battery, will pass current through the vacuum space 35 between the hot filament and the plate provided that the hot filament is made the negative electrode with respect to the source of applied potential.

This phenomenon has been explained by stating that the incandescent body throws 40 off into the evacuated space what are termed corpuscles which are themselves electro-negatively charged masses or particles, the smallest particles into which matter is divisible. And it is explained that the introduction of these corpuscles in effect ionizes the vacuous space so that electricity may 45 pass therethrough. In a sense therefore particles emanating from the incandescent filament or body render the previously non-conducting vacuous space conducting.

According to my invention this principle

or phenomenon is availed of to control the behavior of a vacuum tube or bulb, and more particularly an X-ray tube or bulb.

For an illustration of a mode of practice 55 of my method and of apparatus suitable therefor, particularly in connection with X-ray tubes, reference is to be had to the accompanying drawings, in which:

Figure 1 is a fragmentary side elevation, 60 parts in longitudinal section, of an X-ray tube having applied thereto one form of means for carrying out my invention.

Fig. 1^a is a front elevational view of the cathode of Fig. 1. 65

Fig. 2 is a longitudinal section through the cathode stem of an X-ray tube and parts therein, some being shown in elevation, provided with a different form of means for carrying out my invention. 70

Fig. 2^a is a front elevational view of the cathode and the filament of Fig. 2. 75

Fig. 3 is a longitudinal section similar to that in Fig. 2 showing further means for carrying out my invention. 80

Fig. 3^a is a cross sectional view, parts in section, taken on the line A—A of Fig. 3.

Fig. 4 shows a cathode isolated from the tube together with a modified form of incandescent member. 85

Fig. 4^a is a perspective view of the parts shown in Fig. 4.

Fig. 5 is a longitudinal sectional view through a modified form of cathode the filament shown in elevation. 90

Fig. 6 is a sectional view through a further modification of a cathode and filament. 95

Fig. 6^a is a front elevational view of the cathode of Fig. 6.

Fig. 7 is a fragmentary longitudinal sectional view of a cathode system of an X-ray tube having a modified form of cathode therein. 100

Fig. 7^a is a perspective view of the cathode shown in Fig. 7.

Fig. 7^b is a front elevational view of the same.

Figs. 8 to 11 inclusive are diagrammatic views of different modifications of arrangements of electrical circuits that may be employed in practising my invention.

Referring to Fig. 1, X is a glass bulb of

an X-ray tube having the usual anode stem *a*, from which is supported the anode or target *A*, the bulb *X* having also the usual cathode stem *c* within which is supported 5 the cathode *C* disposed upon the conducting rod *b* supported in the inner glass stem *d* and electrically connected to the wire or other suitable conductor *N* sealed in the glass at the end of the stem *c* in the well known manner, the wire *N* connecting with 10 the negative pole of the source of high potential current for operating the X-ray tube, as in the well known prior practice. In a cavity *e* in the cathode *C* is disposed the filament *f*, such as an incandescent lamp filament, preferably of tungsten, tantalum, platinum or any other suitable material adapted to be raised to high temperature or incandescence by a current passed 15 through the source of said current having its one terminal connected outside of the X-ray tube with the conductor *N* and its other terminal connected outside of the X-ray tube with the conductor *g* which is 20 sealed through the glass wall of the tube and connects with one terminal of the filament *f*, through insulating bushing *h*, the other terminal of the filament *f* connecting with conductor *j* extending through bushing *h'*. The conductor *j* may connect to 25 the cathode *C* at any suitable point either outside or inside of the tube. In the example illustrated the conductor *j* connects to the conductor *N* within the glass seal. 30 The conductors *g* and *j* may be supported by the glass buttons *k*, *k* upon the inner glass stem *d*. Set in the cathode *C* is a disk or plate *m*, of tungsten, tantalum or any suitable material, the filament *f* being disposed close thereto at its rear. The surface 35 contour of disk *m* conforms as nearly as is possible or convenient to that of the cathode.

The X-ray tube having been highly exhausted and sealed off at *u*, if the space within the tube *X* is very highly rarefied, as for example to a degree such that current will sooner leap through the air across an air gap between terminals outside of the 40 tube electrically connected to the anode and cathode and separated, for example, ten inches, no current will pass within the tube between the anode and cathode; but when the filament *f* is raised to incandescence by 45 current passed therethrough heat therefrom is transferred to the metallic disk *m* which in turn is raised to very high temperature, as for example, incandescence, and then the corpuscles or negatively charged particles 50 are thrown off into the vacuous space and the tube will conduct current delivered by the high potential source. By adjusting the amount of current passed through the filament *f* the temperature of the disk *m* may 55 be regulated or determined and the conduc-

tivity or resistance of the X-ray tube *X* controlled or determined. And while the tube, in the example assumed, would not conduct energy upon the application of a potential high enough to produce a spark 70 across an air gap of ten inches outside of the tube, it will now conduct current upon the application of such a potential and indeed of much lower potentials, such, for example, as are capable of causing sparking 75 across only three or four inches of air gap outside of the tube.

And while it is above assumed that the X-ray tube has been pumped or exhausted to a very great degree, it is to be understood 80 that my invention is applicable also to the case where the exhaustion is not carried so far and where there is substantial remanent gases, either remaining after the pumping or existing after the X-ray tube has been 85 operated some time.

In either case however the liberation of the corpuscles affords a mode of controlling the conductivity or resistance of the X-ray tube.

For example, a physician operating an X-ray tube, may close the switch affording communication between the source of high potential current and the terminals of the X-ray tube and thereafter close or regulate 90 the resistance of the filament circuit to control the temperature of the disk *m*. By adjusting the temperature of the disk *m* by adjusting the current through the filament *f* he may procure from his X-ray tube practically any character of X-rays, for example, X-rays of different penetrations and qualities.

And by my invention this manipulation or control of the X-ray tube is greatly simplified in that the X-ray tube electrodes, namely the X-ray tube cathode and anode are themselves employed for the ionization of the vacuous space to the condition for conductivity or desired degree of conductivity without recourse to an additional or separate circuit for ionization purposes.

In the structure above described the filament *f* does not itself provide the corpuscles, but the disk *m* provides them, the filament *f* operating only indirectly for this purpose.

The incandescent filament may however operate to itself directly supply the corpuscles in which case the arrangement may be 12 such as shown in Fig. 2. Here the filament *f* is supported by the glass member *o* carried by the inner glass stem *d*, the filament being disposed in a notch *p* in the cathode *C*. Here the filament connecting wires *j* and *g* are 12 connected respectively with the negative conductor *N* and a source of filament exciting current as in Fig. 1.

Here when the filament *f* is raised to suitable temperature by current passed there-

through it will liberate corpuscles or negatively charged particles with resultant adjustment or control of the conductivity or resistance of the X-ray tube.

- 5 In Fig. 3 the arrangement is similar to that in Fig. 2 except that the cathode C is not notched and the filament f is disposed back of the cathode C, the electrical connections being the same as in Fig. 2. Supported 10 by the cathode C on pins or rods q is the metallic electro-static shield r in electrical communication with the cathode C through the rods q. The shield r is disposed between the filament f and the glass cathode stem c 15 for the purpose of neutralizing any electrostatic attractive effect upon the filament f which would otherwise cause it to deflect over toward and possibly become welded or attached to the inside wall of the glass 20 stem c.

It is to be understood that the electrostatic shield r may be applied to structures other than that shown in Fig. 3 by simple application of the principle of its action 25 above described.

- In Figs. 4 and 4^a the filament takes the form of an incomplete ring f' surrounding the cathode C back of its active surface and standing free therefrom, being supported 30 by wire or other supports s anchored at s' to the inner glass stem d. To the ends of the ring f' are connected the filament circuit conductors g and j for conveying current to the filament as in the cases above described.

- 35 In Fig. 5 the cathode C is provided with a hole or aperture t communicating with the cavity e' within which is disposed the filament f carried by the glass support o' carried by the metallic plug u. One end of the 40 filament connects by wire j with the cathode C while the other passes through insulating bushing u'' and connects with wire g which extends to the exterior of the tube as in the previous cases described.

- 45 In this case again the filament is raised to suitable high temperature whereupon the corpuscles or negatively charged particles emanating therefrom escape into the space of the X-ray tube through the aperture t 50 with the results hereinbefore described.

- In Figs. 6 and 6^a the cathode C is provided in its front or active face with a depression or recess v within which is disposed the filament f'' whose one end j' connects 55 directly with the cathode C and whose other terminal connects through conductor g, passing through insulating bushing h'' and extending to the exterior of the tube as in the other cases described.

- 60 In the arrangement shown in Figs. 7, 7^a and 7^b the cathode C' is made of thin sheet metal or other suitable material provided with the conducting tongues or extensions w and w' of relatively thicker or heavier section than the cathode C'. The tongue w is

electrically and mechanically connected to the cylindrical or similar metallic cup x whose cylindrical edge is sealed into a hollow circular glass portion y on the hollow inner glass stem d', the wall of this portion opposite the stem d' being rounded outwardly, and the conductor N electrically connects with the tongue w through the member x and extends to the outside of the X-ray tube through the tube d' where it is connected, as previously stated, with the negative pole of the source of high potential current for operating the X-ray tube. The other tongue w' is similarly connected to and supported by the metallic cup member x' sealed into the hollow glass button y'. The stem d' is hollow as shown, the inner end wall being indicated at y'' and access into the interior of the stem d' may be had from outside of the X-ray tube, the entry to the hollow tube d' being at d''. The tongue w' is electrically connected through the member x' with the conductor g which extends to the exterior through the tube d'.

In this case a relatively heavy current is 90 passed through the cathode C' itself from a source of energy whose terminals are connected to the conductors N and g. This current raises the temperature of the cathode C' itself to the desired point where it will 95 liberate corpuscles or negatively charged particles at the rate desired, it being remembered that it is connected to the negative pole of the high potential source through conductor N.

Because of the circular shape of the cathode C' its thickness may vary from its center to its periphery along the horizontal dotted line in Fig. 7^b in such manner that the resistances of the myriad conducting 105 paths between the tongues w and w' may be substantially equal. In such case the thickness of the cathode C' at its center is less than at its periphery, and roughly speaking, it is about one and one half times 110 as thick at its periphery as at its center.

With the structure illustrated in Fig. 7 the cathode itself directly supplies the conductivity controlling corpuscles.

In Fig. 8 X is an X-ray tube provided 115 with any of the forms of means for liberating corpuscles, such as those hereinbefore described or their equivalents. The X-ray tube is excited from a source of high potential current, such, for example, as a high 120 potential rectifying system disclosed in prior Letters Patent of the United States No. 954056, comprising the high potential rectifying switch R intervening between the X-ray tube X and the high potential step-up transformer T whose primary, adjustable as to its number of turns by the movable contact 1, receives current through the adjustable resistance 2 through the reversing switch 3 from the alternating current 125 130

generator 4 driven by the electric motor 5 receiving current from the mains or supply conductors 6 and 7.

The anode A of the X-ray tube X connects with the positive terminal of the source of high potential current through the conductor 8 while the cathode, as hereinbefore explained, connects through conductor N with the negative pole of the source of high potential current. Connected in parallel relation with the X-ray tube anode and cathode are the spark gap terminals 9 and 10 for measuring by means of a gap in air outside of the tube the relative resistance of the X-ray tube. The conductor g leading to one terminal of the filament or heating element, as hereinbefore described, connects through adjustable resistance 11 and switch 12 with the terminals of the alternating current generator 4 whereby, when the switch 12 is closed, current will flow from one terminal of the generator 4 through the conductor g and through the heating element, or filament such as hereinbefore described, to conductor N and thence through conductor 13 and adjustable resistance 11 to the other terminal of the generator 4.

The physician or operator closes the line switch 14 and brings the motor 5, generator 4, rectifying switch R up to speed. He then closes the switch 3 and adjusts the resistance 2, or contact 1, or both, to produce the desired high potential delivered by the rectifying switch R. Current will not pass through the X-ray tube X at the desired potential applied, for reasons hereinbefore given, that is, because of the great degree of vacuum in the tube X; or the condition within the tube may be such that current will pass under the influence of this applied potential but in insufficient quantity. In either case he may then close the switch 12 and adjust the resistance 11 until sufficient corpuscles or negatively charged particles are delivered into the vacuous space to produce the desired conductivity or resistance of the X-ray tube X. Or he may first close the switch 12 and adjust the resistance 11 to a previously determined point for which it is known a certain character of rays will be produced by the tube, and he may then close the switch 3 whereupon current will pass through the X-ray tube and produce X-rays in the well known manner, and when the current through the heating element or filament is reduced or broken the current from the high potential source through the X-ray tube will diminish or cease.

It will be noted that in this case, where the filament or heating element derives current through a circuit which is conductively connected to the alternating current generator 4, the negative conductor N is connected to earth E.

In Fig. 9 the arrangement is similar to

that in Fig. 8 except that here the current delivered to the filament or heating element is derived from the direct current supply, or the mains of whatever type of supply, through the adjustable resistance 11 and the switch 12. Here again the negative conductor N is connected to earth E.

In Fig. 10 the connection to earth E may be omitted, since the circuit through the filament or heating element through conductor g is insulated from both the supply conductors and the alternating current generator 4 in that the current through the conductors g and 13 leading to the heating element or filament is derived from the secondary 15 of a small preferably step down transformer T' whose primary winding 16 connects with the terminals of the alternating current generator 4 through the adjustable resistance 17 and the switch 12. In this case the temperature of the filament or heating element may be determined or adjusted by adjusting the resistance 11 or resistance 17, or both.

In Fig. 11 is a fragmentary illustration of an arrangement whereby the filament f, or any other similarly operating heating element or corpuscle delivering element may be traversed by a source of current separate and distinct from that operating the X-ray tube. Here a battery or other source of current 18 has its one terminal, preferably its positive terminal, connected with the conductor g through the switch 12 while its negative terminal connects through the adjustable resistance 11 with the conductor N. Here again the adjustment of the resistance 11, after closure of switch 12, will determine the temperature of the filament f and therefore the conductivity or resistance of the X-ray tube whose cathode is C.

What I claim is:

1. The method of increasing the conductivity of an X-ray tube having an attenuated atmosphere of free gas and main electrodes which are solid, which consists in creating a potential difference between the terminals of the main path of the X-ray tube, rendering a body within said tube electro-negative by subjecting it to substantially the potential of the negative terminal of said main path, and raising said body to a temperature causing emission of corpuscles for increasing the conductivity of said main path.

2. The method of controlling the conductivity of a vacuum tube, which consists in impressing a high potential upon the anode and cathode of a vacuum tube, rendering a body in said tube disposed near the cathode thereof electro-negative by subjecting the same to said same high potential, and raising the temperature of said body by passing a current therethrough.

3. The method of controlling the conductivity of an X-ray tube, which consists in impressing a high potential upon the anode

- and cathode of an X-ray tube, rendering a body in said tube disposed near the cathode thereof electro-negative by subjecting the same to said same high potential, and raising 5 the temperature of said body by passing a current therethrough.
4. The combination with an X-ray tube and its separated anode and cathode for producing X-rays, of means for raising the 10 temperature of said cathode to incandescence, and means for passing current through said means.
5. The combination with an X-ray tube and its separated anode and cathode for producing X-rays, of means for passing near 15 said cathode to raise its temperature a current independent of the tube exciting current.
6. The combination with a vacuum tube 20 and its separated anode and cathode, of a source of high potential current having its negative terminal connected to said cathode, of a conductor within said tube connected to said negative pole of said high potential 25 source, and a second source of current for passing current through said conductor to raise its temperature.
7. The combination with an X-ray tube and its separated anode and cathode, of a 30 source of high potential current having its negative terminal connected to said cathode, of a conductor within said tube connected to said negative pole of said high potential source, and a second source of current for 35 passing current through said conductor to raise its temperature.
8. The combination with a vacuum tube and its separated anode and cathode, of a 40 source of high potential direct current having its negative pole connected to said cathode, of a conductor within said tube near said cathode and connected to said negative pole of said source of current, and a second source of 45 current for raising the temperature of said conductor.
9. The combination with an X-ray tube and its separated anode and cathode, of a 50 source of high potential current having its negative pole connected to said cathode, of a conductor within said tube near said cathode and connected to said negative pole of said source of current, and a second source of current for raising the temperature of said 55 conductor.
10. The combination with a vacuum tube and its separated anode and cathode, of a 60 source of high potential direct current having its negative terminal connected to said cathode, of a conductor within said tube connected to said negative pole of said high potential source, a second source of current for 65 passing current through said conductor to raise its temperature, and means for controlling the strength of the current through said conductor.
11. The combination with an X-ray tube and its separated anode and cathode, of a source of high potential current having its negative terminal connected to said cathode, of a conductor within said tube connected to 70 said negative pole of said high potential source, a second source of current for passing current through said conductor to raise its temperature and means for controlling the strength of the current through said conductor. 75
12. The combination with a vacuum tube and its separated anode and cathode, of a source of high potential current having its negative pole connected to said cathode, of a 80 conductor within said tube near said cathode and connected to said negative pole of said source of current, a second source of current for raising the temperature of said conductor, and means for controlling the strength 85 of the current through said conductor.
13. The combination with an X-ray tube and its separated anode and cathode, of a source of high potential current having its negative pole connected to said cathode, a 90 conductor within said tube near said cathode and connected to said negative pole of said source of current, a second source of current for raising the temperature of said conductor, and means for controlling the strength 95 of the current through said conductor.
14. The combination with a vacuum tube and its separated anode and cathode, of a source of high potential current having its negative pole connected to said cathode, a 100 filament within said tube in electrical communication with said negative pole of said source of current, and a second source of current for raising the temperature of said filament.
15. The combination with an X-ray tube and its separated anode and cathode, of a source of high potential current having its negative pole connected to said cathode, a 105 filament within said tube in electrical communication with said negative pole of said source of current, and a second source of current for raising the temperature of said filament. 110
16. The combination with a vacuum tube and its separated anode and cathode, of a source of high potential current having its negative pole connected to said cathode, a 115 filament disposed within said tube near said cathode and electrically connected with said negative pole of said source, the shortest distance between said anode and said cathode being less than that between said anode and said filament, and a second source of current for raising the temperature of said filament. 120
17. The combination with an X-ray tube and its separated anode and cathode, of a source of high potential current having its negative pole connected to said cathode, a 125 filament disposed within said tube near said 130

cathode and electrically connected with said negative pole of said source, and a second source of current for raising the temperature of said filament.

- 5 18. The combination with the vacuum tube and its separated anode and cathode, of a source of high potential current having its negative pole connected to said cathode, a filament within said tube in electrical communication with said negative pole of said source of current, a second source of current for raising the temperature of said filament, and means for adjusting the current through said filament.
- 10 19. The combination with an X-ray tube and its separated anode and cathode, of a source of high potential current having its negative pole connected to said cathode, a filament within said tube in electrical communication with said negative pole of said source of current, a second source of current for raising the temperature of said filament, and means for adjusting the current through said filament.
- 15 20. The combination with an anode and a solid cathode of a vacuum tube, of a source of high potential connected thereto, a conductor within said tube maintained electro-negative, at high difference of potential with respect to said anode and at approximately the same potential as said cathode, and means for raising the temperature of said conductor.
- 25 21. The combination with the anode and cathode of an X-ray tube, of a source of high potential connected thereto, a conductor within said tube maintained electro-negative, at high difference of potential with respect to said anode and at approximately the same potential as said cathode, and means for raising the temperature of said conductor.
- 30 22. The combination with an anode and a solid cathode of a vacuum tube, of a source of high potential connected thereto, a conductor within said tube maintained electro-negative, at approximately the same potential as said cathode, and at high difference of potential with respect to said anode, and means for passing current through said conductor to raise its temperature.
- 35 23. The combination with the anode and cathode of an X-ray tube, of a source of high potential connected thereto, a conductor within said tube maintained electro-negative, at approximately the same potential as said cathode, and at high difference of potential with respect to said anode, and means for passing current through said conductor to raise its temperature.
- 40 24. The combination with an anode and a solid cathode of a vacuum tube, of a source of current, means deriving energy from said source for impressing high potential upon said anode and cathode, a conductor within

said tube connected with the negative pole of said high potential means, and means deriving energy from said source of current for passing current through said conductor to raise its temperature.

70 25. The combination with the anode and cathode of an X-ray tube, of a source of alternating current, means deriving high potential energy from said source for impressing said high potential upon said anode and cathode, a conductor within said tube connected with the negative pole of said high potential means, and a transformer deriving current from said source of alternating current for passing current through said conductor to raise its temperature.

75 26. The combination with an X-ray tube having an attenuated atmosphere of free gas, of an anode and cathode spaced from each other within said gas, a source of high potential current connected to said anode and cathode, a body within said tube subjected to substantially the same negative potential as said cathode, and means for independently heating said body to a temperature to 85 emit corpuscles to increase the conductivity of the tube.

80 27. In an X-ray tube the combination of an anode; a cathode; a circuit for said anode and cathode; a filament located in said tube adapted when hot to send radiations into the space between said anode and cathode; a second circuit for heating said filament; and a connection between said first and second named circuits, substantially as described.

85 28. In an X-ray tube the combination of an anode; a cathode; a circuit for said anode and cathode; a filament located in said tube adapted when hot to send radiations into 105 the space between said anode and cathode; a second circuit for heating said filament; a switch and an adjustable resistance in said second circuit; and a connection between said first and second named circuits, 110 substantially as described.

90 29. The method of controlling the conductivity of a vacuum tube, which consists in impressing greatly different potentials upon the main electrodes respectively, simultaneously impressing a low potential upon a body within said tube, and raising the temperature of said body to such a degree that one of the main electrodes is heated thereby to cause negatively charged corpuscles to be 115 emitted, said body being never at a potential higher than that of the main electrode which is charged to the higher potential.

95 30. The combination with an X-ray tube and its separated anode and cathode for producing X-rays, of means spaced from said cathode for raising the temperature of said cathode to incandescence, and means for passing current through said means.

100 31. The combination with the anode and

cathode of a vacuum tube, of a body disposed behind said cathode and shielded thereby from bombardment impinging upon the front of said cathode, and means for raising 5 said body to a temperature for emitting corpuscles.

32. The combination with the anti-cathode and cathode of an X-ray tube, of a body subjected to substantially the same potential as 10 said cathode and disposed behind the same and shielded thereby from bombardment impinging upon the front of said cathode, and means for independently heating said body to a temperature to emit corpuscles.
- 15 33. An X-ray tube comprising an anti-cathode and a cathode structure coöperating therewith having a corpuscle-emitting part of small heat capacity, a conductor disposed near said part to heat the same, and means 20 for maintaining said conductor at a temperature which will cause said part of small heat capacity to glow.

34. In vacuum tube apparatus, the combination with a cathode having a concave 25 active surface and a portion disposed near the center of said surface having a small heat capacity, of heating means disposed near said portion to maintain said portion at a high temperature during operation.
- 30 35. In vacuum tube apparatus, the combination with a cathode comprising an element having a recess therein, one wall of said recess being of thin metal, of a heating coil in said recess, and means for supplying 35 current to said coil.

36. In vacuum tube apparatus, the combination with an electrode comprising an element having a recess therein, of a heating coil in said recess, terminals for said heating 40 coil, one of said terminals being in electrical connection with said element, and a source of heating current connected to said terminal.

37. An X-ray tube comprising an anti-cathode, a concave cathode for focusing cath-

ode rays upon an anti-cathode, a body disposed near said cathode and subjected to substantially the same potential, and means for independently heating said body to a temperature to emit corpuscles.

50

38. An X-ray tube comprising an anti-cathode, a concave cathode for focusing cathode rays upon said anti-cathode, and means for independently heating a portion of the concave surface of said cathode to a 55 temperature to emit corpuscles.

39. In vacuum tube apparatus, the combination with a cathode having a concave face, a portion disposed near the center of said surface having a small heat capacity, 60 the contour of its face being approximately the same as that of the cathode face, of heating means for heating said portion.

40. In vacuum tube apparatus, an electrode having a concave face, a portion of 65 which only is corpuscle emitting, a part at least of said corpuscles being emitted independently of bombardment of the electrode.

41. In vacuum tube apparatus, an electrode element having a concave corpuscle 70 emitting face, a part at least of said corpuscles being emitted independently of bombardment of the electrode element.

42. In vacuum tube apparatus, an electrode having a concave face, a portion of 75 which only is corpuscle emitting, said portion emitting corpuscles independently of the presence or absence of gas in the tube.

43. In vacuum tube apparatus, an electrode element having a concave corpuscle 80 emitting face, said element emitting corpuscles independently of the presence or absence of gas in the tube.

In testimony whereof I have hereunto affixed my signature in the presence of the 85 two subscribing witnesses.

EDWIN WALKER KELLY.
